PUNCHING MECHANISM

Job D. Baker, Gilbertville, Mass., assignor to Sullivan Machinery Company, a corporation of Massachusetts

Application November 22, 1933, Serial No. 699,211

28 Claims. (Cl. 76—5)

This invention relates to punching mechanisms, and more particularly to punching mechanisms of the pressure fluid actuated percussive type for opening or pinning out the holes in hollow rock drill steel during the forging operation.

An object of this invention is to provide an improved punching mechanism. Another object is to provide an improved punching mechanism of the pressure fluid actuated percussive type for opening the holes in hollow rock drill steels during the forging operation. A further object is to provide an improved punching mechanism wherein the pinning out tool is hammered into and released from the rock drill steel in an improved manner. Yet another object is to provide an improved valve control mechanism for the hammer motor of such a punching mechanism. These and other objects will, however, herein-after more fully appear.

In the accompanying drawing there is shown, for purposes of illustration, one form which the invention may assume in practice.

In this drawing,—

Fig. 1 is a longitudinal vertical sectional view through the illustrative form of the improved punching mechanism, the hammering mechanism thereof shown in pinning-in position.

Fig. 2 is a view similar to Fig. 1, showing the hammering mechanism in pinning-out position.

Fig. 3 is a view similar to Figs. 1 and 2, showing the hammering mechanism in its inoperative or shut-down position.

In this illustrative embodiment of the invention, there is shown a punching mechanism generally designated 1, generally comprising a fluid actuated hammering mechanism 2 supported on a suitable supporting frame 3:

The hammering mechanism 2, as shown in the drawing, comprises a pressure fluid actuated hammer motor having a motor cylinder 4 containing a reciprocable hammer piston 5. This hammer piston is provided with a forwardly projecting striking bar 6 for transmitting hammer blows to the shank 7 of a usual collared pinning-out tool or punch pin 8. This pin shank is supported within a chuck 9 carried within the front part of the motor cylinder. The punch pin collar is indicated at 10. Secured to the rear end of the motor cylinder is a rear head member 11, a valve chest member 12 and a rear head block 13, these parts being held in assembled relation with respect to the cylinder in any suitable manner. The rear head block is cylindrical in form and is guided for reciprocatory movement in a concave recess or guideway 14 formed on the supporting

frame 3, the forward end of the motor cylinder being guided at 15 on the supporting frame. As shown, the supporting frame has upstanding arms 16 straddling the motor cylinder and supporting a releasable pin 17 for holding the hammer mechanism within its guides on the supporting frame. The rear end wall 18 of the rear guide 14 forms an abutment or rear stop for limiting rearward movement of the hammer control mechanism, while a yoke-shaped abutment 19 forms a front stop for limiting forward movement of the hammer control mechanism, the punch pin of the hammer mechanism projecting forwardly through a vertical slot 20 formed in this yoke. The yoke 19 also forms a retainer for precluding forward release of the punch pin from its chuck.

The hammer motor is preferably of a standard type, and the valve mechanism thereof for distributing pressure fluid to the motor cylinder to effect rapid reciprocation of the hammer piston comprises a usual automatic fluid distributing valve 21 guided for reciprocatory movement in a bore 22 formed in the valve chest member 12 and controlling the supply of motive fluid flowing through a passage 23 to the motor cylinder and the exhaust of fluid from the motor cylinder through a usual exhaust passage 24. Attached to the rear head block 13 is a fluid supply pipe 25 projecting downwardly through a slot 26 formed in the guide portion of the supporting frame, and this pipe engageable with the slot ends limits movement of the hammering mechanism in its guides. A passage 27 connects this supply pipe with a longitudinally extending axial valve bore 28 formed in the head block 13. Reciprocable in this bore 28 is a throttle valve 29 having a groove 30 for connecting the supply passage 27 with the supply passage 23. A passage 31 connects the supply passage 27 with the bore 28 at the forward side of the throttle valve 29 so that the throttle valve is constantly urged toward its rearmost closed position.

The improved means for controlling the throttle valve 29 for holding the latter open during forward movement of the hammer mechanism so that operation of the hammer piston is effected during withdrawal or retractive movement of the drill steel, herein comprises a valve control member, herein in the form of a yoke-shaped member 33 guided between the arms 16 and having a longitudinal portion 34 overlying the hammer motor and downwardly bent front and rear ends 35 and 36. The rear end 36 of this yoke member extends downwardly between the rear end of the

head block 13 and the rear abutment 18, and has a circular recess 37 for receiving the rear end of the throttle valve 29, while the forward end 35 of the yoke member is provided with an opening 38 5 through which the punch pin loosely projects and arranged between the front end of the motor and the front abutment 19.

The operation of the improved punch mechanism will be clearly apparent from the description given. During the forging of the cutting end 10 of the drill steel S, the central hole therein is wholly or partially closed, and to open up or pin out this hole the drill steel S is placed in the position shown in Fig. 1 against the forward end 15 of the punch pin 8. The drill steel is then moved inwardly toward the hammer mechanism, thereby shoving the punch pin rearwardly, and as a result, the hammer mechanism is moved bodily rearwardly in its guides relative to the supporting frame, to the position shown in Fig. 1. At 20 this time the rear end 36 of the yoke member 33 is held against the rear abutment 18 with the throttle valve 29 held in abutting relation with the bottom of the recess 37 by the action of the pressure fluid acting on the forward area of the 25 valve, and as the hammer motor was moved rearwardly in its guides the passages 27 and 23 were moved into a position wherein the groove 30 in the throttle valve connects the same, and as a result 30 pressure fluid is admitted to the motor cylinder to effect reciprocation of the hammer piston. Upon further rearward movement of the drill steel, the punch pin is driven into the drill steel bore. When the drill steel S is pulled rearwardly to withdraw the steel from the punch mechanism and the punch pin is stuck within the steel bore, the punch pin is pulled outwardly relative to the motor cylinder, thereby bringing the collar 10 thereon into engagement with the front 35 end 35 of the yoke member 33, thereby moving the hammer mechanism into the position shown in Fig. 2, with the throttle valve 29 held in its open position by the yoke member, and as a result, as the hammer mechanism is moved forwardly the punch pin 8 is loosened or freed from 40 the drill steel bore. It will thus be seen that the operation of the hammer is continued during retraction of the drill steel, and the hammering action thereof on the pin 8 effects release of the latter from the steel bore. When the punch pin 45 is freed from the steel, the yoke member 33 is free to move rearwardly to release the throttle valve, and the pressure fluid acting on the forward end of the throttle valve quickly moves the latter into its rearmost closed position, as shown 50 in Fig. 3; and as a result, action of the hammer motor stops. The forward pin freeing movement of the hammer mechanism is a rapid operation, and quick pin release is frequently effected by 55 but a single hammer blow on the punch pin shank, the hammer mechanism jumping back upon engagement with the front abutment 19 with a sort of repercussion and the hammer thereof immediately stopping before the hammer can strike the front end of the valve control yoke 33 when the latter has moved away from the front abutment 19. It will thus be seen that the control valve 29 is maintained open by engagement 60 with the rear abutment 18 during the hammering-in operation and by the yoke 33, which is distinct from the rear abutment 18, during the hammering-out operation.

Under actual operating conditions, the improved punch mechanism has been found to be 75 highly effective in opening or pinning out the

holes in rock drill steels and for releasing a stuck pin from the steel bore, the retractive hammering action effectively freeing a stuck pin from the steel bore. Moreover, it will be noted that the improved punch mechanism is of an extremely 5 simple and rugged construction which may be manufactured and kept in repair at a minimum of expense. These and other uses and advantages of the improved punch mechanism will be clearly apparent to those skilled in the art.

While I have in this application specifically described one form which the invention may assume in practice, it will be understood that this form is shown for purposes of illustration and that the invention may be modified and embodied 15 in various other forms without departing from its spirit or the scope of the appended claims.

What I claim as new and desire to secure by Letters Patent is:

1. In a punching mechanism, a fluid actuated 20 hammer motor, a valve for controlling the supply of motive fluid to said motor, a pinning out tool actuated by said motor, and means actuated by movement of the pinning out tool relative to the motor and operatively connected to 25 said valve independently of said motor for controlling said valve.

2. In a punching mechanism, a supporting frame, a hammer motor guided for longitudinal movement forwardly and rearwardly along said 30 frame, a punch pin percussively actuated by said hammer motor and to which pressure is adapted to be applied by engagement of the work therewith for controlling movement of said hammer motor forwardly and rearwardly along said frame, and means embodying means associated with said punch pin for controlling actuation of said hammer motor, movement of said hammer motor into its rearward position by application of a rearward pressure by the work on the punch pin causing said control means to effect motor actuation to drive percussively the punch pin into the work, and movement of said hammer motor into its forward position by application of a forward pressure by the work on the punch pin causing said control means to effect motor actuation to release percussively the punch pin from the work.

3. In a punching mechanism, a frame having 50 guiding means, a hammering mechanism guided for back and forth movement in said guiding means, a punch pin percussively actuated by said hammer mechanism and against which pressure is adapted to be applied by engagement of the work therewith for controlling movement of said hammering mechanism back and forth in said guiding means, and means for causing said hammering mechanism to operate to effect hammering of the punch pin when said hammer mechanism is in either its rearward or forward position relative to said frame guiding means.

4. In a punching mechanism, a fluid actuated hammer motor, a valve for controlling the supply of motive fluid to said motor, a pinning out tool actuated by said motor, and means actuated by movement of the pinning out tool relative to the motor for controlling said valve and including a yoke-shaped member extending along one side of the hammer motor and engageable with the pinning out tool and said controlling valve.

5. In a punching mechanism, a fluid actuated hammer motor, a valve carried within the rear end of the hammer motor for controlling the supply of motive fluid to said motor, a pinning out tool carried within the forward end of the

hammer motor and actuated thereby, and means actuated by movement of the pinning out tool relative to the hammer motor for controlling said valve and including a member extending along 5 one side of the hammer motor and engageable at its rear end with said valve and at its forward end with said pinning out tool.

6. In a punching mechanism, a fluid actuated hammer motor, a valve carried within the rear 10 end of the hammer motor for controlling the supply of motive fluid to said motor, a pinning out tool carried within the forward end of the hammer motor and actuated thereby, and means actuated by movement of the pinning out tool 15 relative to the hammer motor for controlling said valve and including a member extending along one side of the hammer motor and engageable at its rear end with said valve and at its forward end with said pinning out tool, the forward 20 end of said member having an opening through which said pinning out tool projects.

7. In a punching mechanism, a supporting frame having front and rear abutments and guiding means arranged between said abutments, a 25 hammer motor guided for endwise reciprocatory movement in said guiding means relative to said frame and between said abutments, a valve carried within the rear end of the hammer motor for controlling the actuation thereof, a pinning 30 out tool supported within the forward end of the hammer motor for actuation thereby, said pinning out tool having a collar thereon, and means for controlling said valve by movement of the pinning out tool relative to the hammer motor 35 including a yoke-shaped member extending along one side of the hammer motor and having a front end portion extending between the pin collar and the front abutment and a rear portion 40 extending between the rear abutment and the valve.

8. In a punching mechanism, a supporting frame having front and rear abutments and guiding means arranged between said abutments, a 45 hammer motor guided for endwise reciprocatory movement in said guiding means relative to said frame and between said abutments, a valve carried within the rear end of the hammer motor for controlling the actuation thereof, a pinning 50 out tool supported within the forward end of the hammer motor for actuation thereby, said pinning out tool having a collar thereon, means for controlling said valve by movement of the pinning out tool relative to the hammer motor including a yoke-shaped member extending along 55 one side of the hammer motor and having a front end portion extending between the pin collar and the front abutment and a rear portion extending between the rear abutment and the valve, said member maintaining said valve in open position 60 during forward movement of the hammer motor in its guides, and means for effecting automatic closing of the valve when the punch pin is released.

9. In a punch mechanism, a support having a 65 longitudinally extending guideway, a hammer mechanism slidably guided in said guideway, a pinning out tool actuated by said hammer mechanism, a valve opened by rearward longitudinal movement of said hammer mechanism in said 70 guideway for effecting actuation of said hammer mechanism to actuate percussively said pinning out tool to drive the latter into the work, and means for maintaining said valve open during forward longitudinal movement of said hammer mechanism in its guideway to effect actuation of 75

said hammer mechanism to actuate percussively said pinning out tool to release the latter from the work.

10. In a punch mechanism, a support having a longitudinally extending guideway, a hammer mechanism slidably guided in said guideway, a pinning out tool actuated by said hammer mechanism, a valve opened by rearward longitudinal movement of said hammer mechanism in said guideway for effecting actuation of said hammer mechanism to actuate percussively said pinning out tool to drive the latter into the work, and means for maintaining said valve open during forward longitudinal movement of said hammer mechanism to actuate percussively said pinning out tool to release the latter from the work, said latter means including means operatively connected to said valve and said pinning out tool. 15

11. In a punch mechanism, a support having a longitudinally extending guideway, a hammer mechanism slidably guided in said guideway, a pinning out tool actuated by said hammer mechanism, a valve opened by rearward longitudinal movement of said hammer mechanism in said guideway for effecting actuation of said hammer mechanism to actuate percussively said pinning out tool to drive the latter into the work, and means for maintaining said valve open during forward longitudinal movement of said hammer mechanism in its guideway to effect actuation of said hammer mechanism to actuate percussively said pinning out tool to release the latter from the work, said means comprising an element extending between said pinning out tool and said valve and engaging the latter for maintaining said valve open during said forward longitudinal movement. 30

12. In a punch mechanism, the combination of a cylinder having a piston chamber and a hammer piston in said piston chamber, a working 40 implement having a shank provided with a rear impact surface and adapted to be actuated percussively by said hammer piston, means for effecting actuation of said hammer piston to drive, by the direct hammering action of the hammer 45 piston on the rear impact surface on the rear end of the working member shank, said working implement into the work, and means associated with and actuated by movement of said working implement with respect to said cylinder to effect 50 actuation of said hammer piston to release, by the direct hammering action of the hammer piston on the rear impact surface on the rear end of the working implement shank, said working implement from the work. 55

13. In a punch mechanism, a support having a guideway, a hammer mechanism guided on said guideway and comprising a cylinder having a piston chamber and a piston reciprocable in said chamber, a punch pin actuated by said hammer 60 mechanism, a valve mechanism operated by movement of said hammer mechanism in a rearward direction along its guideway to effect actuation of the hammer piston to drive the punch pin into the work, and means associated with and 65 actuated by said punch pin for holding said valve mechanism open during forward movement of the hammer mechanism along its guideway to cause said hammer mechanism to effect release of the punch pin from the work. 70

14. In a punch mechanism, a support having a guideway, a hammer mechanism guided on said guideway and comprising a cylinder having a piston chamber and a piston reciprocable in said chamber, a punch pin actuated by said hammer 75

- mechanism, a valve mechanism operated by movement of said hammer mechanism in a rearward direction along its guideway to effect actuation of the hammer piston to drive the punch pin 5 into the work, and means associated with and actuated by said punch pin for holding said valve mechanism open during forward movement of the working mechanism along its guideway to cause said hammer mechanism to effect release of the 10 punch pin from the work, said latter means including a member engageable with the punch pin and operatively connected to the valve mechanism for holding the latter open during such forward movement of said hammer mechanism 15 along its guideway.
15. In a punch mechanism, a support having a guideway and end abutments, the forward abutment having an opening, a hammer mechanism slidably guided on said guideway between 20 said abutments, a collared punch pin actuated by said hammer mechanism and projecting through the opening in the forward abutment, a valve mechanism operated by movement of said hammer mechanism in a rearward direction along 25 said guideway to effect actuation of the hammer mechanism to drive the punch pin into the work, and means, including a member having an opening through which the punch pin projects and engageable by the pin collar and extending into 30 a position with a portion thereof interposed between the rear abutment and said valve mechanism, for operating said valve mechanism during forward movement of the hammer mechanism along its guideway to cause said hammer mechanism 35 to effect release of the punch pin from the work.
16. In a punching mechanism, a supporting frame having front and rear abutments and guiding means arranged between said abutments, 40 a hammer motor guided for endwise reciprocatory movement in said guiding means relative to said frame and between said abutments, a valve carried within the rear end of the hammer motor for controlling the actuation thereof, a pinning out tool supported within the forward end of the hammer motor for actuation thereby, said pinning out tool having a collar thereon, and means for controlling said valve by movement 45 of the pinning out tool relative to the hammer motor including a valve controlling member extending along one side of the hammer motor and having a front end portion extending between the pin collar and the front abutment and a rear portion extending between the rear abutment 50 and the valve.
17. In a punching mechanism, a supporting frame having front and rear abutments and guiding means arranged between said abutments, a hammer motor guided for endwise reciprocatory 55 movement in said guiding means relative to said frame and between said abutments, a valve carried within the rear end of the hammer motor for controlling the actuation thereof, a pinning out tool supported within the forward end of the hammer motor for actuation thereby, said pinning out tool having a collar thereon, means for controlling said valve by movement of the pinning out tool relative to the hammer motor including a valve controlling member extending 60 along one side of the hammer motor and having a front end portion extending between the pin collar and the front abutment and a rear portion extending between the rear abutment and the valve, said member maintaining said valve in 65 open position during forward movement of the 70

hammer motor in its guides, and means for effecting automatic closing of the valve when the punch pin is released.

18. In a punch mechanism, a support having a guideway, a pressure fluid actuated hammer motor 5 slidably guided on said guideway, a punch pin having a shank supported in position to receive the impact blows of said hammer motor, a valve opened by rearward movement of said hammer motor in its guideway to effect actuation of the 10 hammer motor to actuate percussively the punch pin to drive the punch pin into the work, and means for maintaining said valve open during forward movement of the said hammer motor in its guideway to effect actuation of the hammer 15 motor to actuate percussively said punch pin shank to loosen the punch pin in the work during such forward movement, said hammer motor having a hammer element for delivering impact blows directly to the punch pin shank during 20 both rearward and forward movements of said hammer motor along its guideway.

19. In a punch mechanism, a support having a guideway, a pressure fluid actuated hammer motor 25 slidably guided on said guideway, a punch pin having a shank supported in position to receive the impact blows of said hammer motor, a valve opened by rearward movement of said hammer motor in its guideway to effect actuation of the 30 hammer motor to actuate percussively the punch pin to drive the punch pin into the work, and means for maintaining said valve open during forward movement of the said hammer motor in its guideway to effect actuation of the hammer motor to actuate percussively said punch pin 35 shank to loosen the punch pin in the work during such forward movement, said hammer motor having a hammer element for delivering impact blows directly to the punch pin shank during both rearward and forward movements of 40 said hammer motor along its guideway, said hammer motor and said latter means moving automatically into inoperative position to close said valve to shut down the punch mechanism when the punch pin is released from the work.

20. In a punch mechanism, a hammer motor having an impact element, a punch pin actuated thereby and having a shank provided with a rear impact surface adapted to receive the impact blows of said impact element, and means controlled by engagement of the work with the punch pin for effecting actuation of the hammer motor to actuate, by a direct hammering action of said impact element on said rear impact surface on the punch pin shank, the punch pin to drive the latter into the work and to effect release thereof from the work.

21. In a punching mechanism, a fluid actuated hammer motor, a valve for controlling the supply of motive fluid to said hammer motor, a pinning out tool actuated by said motor, and means actuated by engagement of the work with said pinning out tool for controlling said valve to effect motor actuation thereby to actuate by a hammering action the pinning out tool to drive the latter into the work and to effect release of the tool from the work and including valve operating means operatively connected to the valve independently of the motor, said controlling means embodying means for maintaining said valve in operative position by engagement of the pinning out tool with said last mentioned means during the release of the pinning tool from the work.

22. In a punch mechanism, the combination of 75

5 a pressure fluid actuated hammer motor having a cylinder and a hammer piston in said cylinder, a supporting frame for said hammer motor, a working implement adapted to be percussively actuated by said hammer piston, means for controlling the supply of pressure fluid to said hammer motor, means for operating said control means to effect actuation of said hammer motor to cause said hammer piston to actuate percussively said working implement in a forward direction for driving the working implement into the work, and means associated with and actuated by movement of said working implement with respect to said cylinder for operating said 10 control means to effect actuation of said hammer motor to cause said hammer piston to actuate percussively said working implement in a forward direction for releasing said working implement from the work, said control means assuming different positions with respect to said motor support during the driving in and releasing operations of said hammer motor.

23. In a punching mechanism, a support having a guideway, a hammer motor mounted for back and forth movements on said guideway, a punch pin actuated by said hammer motor and to which pressure is adapted to be applied by the work for controlling movement of said hammer motor into its rearward and forward positions on said guideway, and control means for said motor operative when said motor is in its rearward position to effect actuation thereof to drive the punch pin into the work and embodying means operative when said motor is in its forward position to effect actuation of said motor to release the punch pin from the work.

24. In a punching mechanism, a hammer motor, control means for said motor, a punch pin actuated by said hammer motor and to which pressure is adapted to be applied by the work for operating said control means to effect motor actuation, said punch pin having a shank provided with a rear impact surface on its rear end, pressure being applied in a rearward direction by the work to the punch pin to operate said control means to effect motor actuation to drive, by the direct impact of the hammer motor on the rear impact surface on the rear end of the punch pin shank, the punch pin into the work, said controlling means embodying means operated by pressure applied to the punch pin by the work in a forward direction to operate said control means to effect motor actuation to release, by the direct impact of the hammer motor on the rear impact surface on the rear end of the punch pin shank, the punch pin from the work, elements of said control means assuming different bodily located positions during the driving in and releasing operations.

25. In a punching mechanism, a fluid actuated hammer motor, a valve for controlling the supply of motive fluid to said motor, a pinning out tool actuated by said motor, and means actuated by movement of said pinning out tool relative to said motor and including an operating connection connected to said pinning out tool and valve and movable relative to said motor for controlling said valve to effect actuation of said motor to release the pinning out tool from the work. 5 10

26. In a punching mechanism, a fluid actuated hammer motor mounted for bodily movement forwardly and rearwardly, a valve for controlling the supply of motive fluid to said motor, a pinning out tool actuated by said motor, means 15 for controlling said valve when said hammer motor is in its rearward position to effect actuation of said pinning out tool, and means embodying means distinct from said controlling means for controlling said valve to effect actuation of said 20 pinning out tool when said motor is in its forward position, said valve and certain elements of its controlling means moving bodily with said hammer motor during movement of the latter from its rearward position to its forward position. 25

27. In a punch mechanism, a hammer motor having an impact element, a punch pin actuated thereby and having a shank provided with a rear impact surface on its rear end adapted to receive the impact blows of said impact element, 30 and means controlled by movement of said punch pin selectively in opposite directions by engagement of the work therewith for effecting actuation of said hammer motor during both directions of movement of said punch pin to actuate, 35 by a direct hammering action of said impact element on said rear impact surface on the rear end of the punch pin shank, the punch pin to drive the latter into the work and to effect release thereof from the work. 40

28. In a punch mechanism, a hammer motor having an impact element, a punch pin actuated thereby and having a shank provided with a rear impact surface on its rear end adapted to receive the impact blows of said impact element, 45 means controlled by movement of said punch pin by engagement of the work with said punch pin for effecting actuation of said hammer motor to drive, with a direct hammering action of said impact element on said rear impact surface on 50 the rear end of the punch pin shank, the punch pin into the work, and cooperating means controlled by movement of the punch pin in the opposite direction by engagement of the work therewith to release, by a direct hammering action of said impact element on said impact surface on the rear end of the punch pin shank, the punch pin from the work. 55
